A. ZUR

WINDOW LATCH

Filed July 16, 1923

UNITED STATES PATENT OFFICE.

ANTON ZUR, OF CHICAGO, ILLINOIS.

WINDOW LATCH.

Application filed July 16, 1923. Serial No. 651,954.

My invention has for its object the production of a window frame, and relates more particularly to that class wherein the sash of the window is so constructed that convenient access may be had for washing either side of the window pane, or for renewing and replacing a pane of glass, the construction being such that the upper and lower sashes of the window may be turned to horizontal position inside of the room.

I so arrange the pivots that the window sash can swing without interference with the screen or storm window, if the latter be in place, disposing the pivots at the lower corners of the inner face of each sash so that the sash may swing without striking the screen or storm window, and therefore the latter do not have to be removed.

It is to be noted that there is no bottom strip to the outer sash in which the inner sash is mounted for the sash to strike against, but the latter rests directly upon the window sill free to swing when desired.

These and other objects and advantages of the use of my invention will be herein-after more specifically explained.

In the accompanying drawings I have illustrated what I now consider the preferred form of an embodiment of the essential features of my invention and in these drawings—

Figure 1 is a front elevation, partly in section of a window frame with my improved sash therein,

Figure 2 is a vertical sectional view of the same,

Figure 3 is an enlarged sectional detail of one of the attaching members taken on line 3—3 of Figure 1,

Figure 4 is a plan view of the same,

Figure 5 is a fragmentary detail of the divided upper end of the lower sash of the window,

Figure 6 is a plan view of the locking mechanism applied to each sash,

Figure 7 is a vertical sectional view of said lock taken on line 7—7 of Figure 1.

Referring to the drawings 8 represents a window frame or casing which may be of the construction now in general use, the outer and inner walls of which are spaced apart to form channels within which the weights 9—9 are hung. These weights are connected by cords to each window sash extending over the pulleys 10—10 supported

by the window frame in the usual and well known manner.

An outer or auxiliary window sash comprising side members 11, and the top 12, is placed within the inner wall of the window frame 8. Arranged between the tops of the side members of the outer sash of the lower window is a transversely extending frame member 14, which is formed of two pieces, detachably joined together by the screws 15 (Figure 5).

The upper sash frame 16 and the lower sash frame 17 are placed within the aforesaid outer sashes or frames, the outer sashes or frames being arranged to slide up and down within the channels in the window frame and supported by the counterbalance weights 9 in exactly the same manner as in windows commonly employed. A pivot latch 18 is provided at each of the lower corners of each sash 16 and 17. Housings 19 are provided on the inside of the sash frames for these pivot latches. Extending from the latch, through a slot 20, is a knob 21, by means of which the latch may be moved in either direction, to engage or disengage with a socket provided in the side style of the corresponding outer or auxiliary sash.

Extending over the pulleys 10 are the cords 22—22, which support the weights 9—9 on each side of the window. Each window sash 16 and 17 is provided with locking mechanism arranged on each side thereof, which locking mechanism is more clearly shown in Figures 6 and 7.

A casing formed by the metal plate 23 is attached to the sash frame at any convenient position.

A bolt 24 is supported in this casing and is adapted to register with a corresponding socket opening provided in the outer or auxiliary sash of the window. This bolt is movable transversely by means of the cam 25, which is supported upon a shaft 26, mounted in said plate 23. It will thus be seen that the invention does not relate to the manner of mounting the window sashes in the frame but resides in the provision of an outer or auxiliary sash within which the inner or true window sash is pivotally and removably supported.

A link member 27 is attached to the cam 25 and by the connecting member 28 to the bolt 24. A spring 29 has connection with

the link 27 and at its opposite end to any stationary point on the casing 23. A knob extends through a slot in the casing and has connection with the cam 25. As seen in Figures 6 and 7, the cam 25 has notches 25^a and 25^b for cooperation with a pin or the like 33 relatively fixed as seen in Figure 6 to limit the movement of the bolt 24 in both directions.

10 The spring holds the bolt in normal position to engage the socket in the outer or auxiliary sash. To open the window sash, the knob is turned, the latch is moved backwardly out of its socket, to permit its disengagement with the outer sash, and to allow the window sash to be lowered on the pivots 15 18, arranged in the lower corners of each outer sash of the window.

A recessed portion 30 is provided in each 20 of the window frames 11, approximately mediate the top and bottom of each sash. Secured in this recess is a fastening member 31, one end of which is attached to the side of the window frame 11, the opposite 25 end being provided with a hook or other engaging means adapted to take over a pin 32, projecting from the side of the window sash, to hold the sash in partially open position as shown in dotted lines in Figure 2.

30 The window is thus supported when being used for ventilating purposes. It will be observed that I have provided a window which may be placed within any window frame now in common use. When adjusted 35 in position, the upper and lower sashes of

the window may be operated independently of each other. When it is desired to wash the upper sash of the window, the lower sash is pushed upwardly to the top of the frame and the upper sash is lowered to the bottom of the frame, thereby reversing the position of the upper and lower sashes and making it convenient to turn the upper sash to horizontal position while in the lower part of the window frame and easy of access for cleaning purposes. 40 45

I claim:

1. A window, a window sash slidable therein, and a latch therefor comprising a rotatable member having a notch, a bolt, a link connection between said member and bolt, a spring connected at one end to one of the said links, a plate to which all of said elements are affixed, and a pin fixed in the said plate and in position to engage in said notch. 50 55

2. A window, a window sash slidable therein, and a latch therefor, comprising a revolvable member, a bolt, a link pivotally connected to said revolvable member, a member disposed angularly with relation to said link and pivotally connected therewith at one end and at the other end affixed to said bolt, and a spring connected at one end to a fixed support and at the other end to said link between the ends of the latter. 60 65

In testimony whereof I have signed this specification.

ANTON ZUR.
